UNITED STATES PATENT OFFICE.

D JACOB DANIEL, OF LITTLE ROCK, ARKANSAS.

TELEPHONE ATTACHMENT.

1,147,312.

Specification of Letters Patent. Patented July 20, 1915.

Application filed August 19, 1914. Serial No. 857,525.

To all whom it may concern:

Be it known that I, D JACOB DANIEL, a citizen of the United States, residing at Little Rock, in the county of Pulaski and State of Arkansas, have invented certain new and useful Improvements in Telephone Attachments, of which the following is a full, clear, and exact description, reference being had to the accompanying drawings, forming a part hereof.

My invention has relation to improvements in telephone attachments; and it consists in the novel features of construction more fully set forth in the specification and pointed out in the claim.

In the drawings, Figure 1 is a side elevation of a telephone, showing the application of my invention; Fig. 2 is an enlarged front face elevation of the attachment; Fig. 3 is a vertical cross-section on the line 3—3 of Fig. 2; Fig. 4 is a horizontal cross-section on the line 4—4 of Fig. 2; Fig. 5 is a front face elevation of the attachment, with the slide or cover removed; and Fig. 6 is a detail of a section of the web or tape.

The object of my invention is to provide an attachment which may be removably secured to the mouth-piece of the ordinary telephone transmitter, said attachment being provided with a web mounted on a roll from which it may be periodically unwound across the edge of the mouth piece and thereby serve not only to protect the lips of the speaker against contact with the mouth-piece, but the said web may, in addition, carry a suitable calendar, the dates of which are exposed to the view of the person speaking into the transmitter, or the web may carry suitable advertising matter or both according to circumstances. The web is preferably impregnated with any suitable germ-proof and germicidal composition known to the trade, so as to serve as a sanitary membrane directly receiving the sound waves from the mouth of the speaker.

The advantages of the invention will be best apparent from a detailed description thereof, which is as follows:

Referring to the drawings, 1 represents an ordinary telephone transmitter and 2 the usual flaring mouth-piece thereof. Adapted to be passed over the walls of the mouth-piece at a point slightly rearward of the free edge thereof, is a plate 3, the plate having cut therefrom a substantially U-shaped opening U, the edges of the opening span-

ning substantially one-half of the peripheral wall of the mouth-piece. The friction between the sides or fork-arms 3', 3', thus carved out of the plate, is sufficient to hold the attachment to the mouth-piece. Formed integrally with said arms 3', 3', and directed outwardly, are flanges 4, 4, which are provided with marginal lips 5, 5, the flanges 4, 4, serving to span the sides of the mouth-piece as shown and extending slightly beyond the outer edge thereof. The plate 3, which, together with its arms 3', 3', forms a saddle adapted to be passed over the mouth-piece, is carried by, or is formed integrally with, a casing 6 which serves as a housing for a roll of paper or equivalent aseptic and sanitary web or tape w, on which is printed any convenient form of calendar C, between successive dates of which may be distributed advertising matter A, as shown. The open top of the casing is closed by a sliding cover 7, which is received between the flanges 4, 4, aforesaid, and between the edge of the mouth-piece and the lips 5, 5, as clearly seen from the drawings. One end of the slide or cover 7 is provided with a finger-hold 8, by which it may be readily manipulated, and with side limiting lugs 9, 9. The formations 4, 5, serve as grooves or ways for the slide 7, and when the slide is inserted into the ways it is limited in one direction by the lugs 9 which come in contact with the casing wall. When the slide is fully inserted the inner edge e thereof projects a suitable distance beyond the terminals of the forks 3', 3', and of the flanges 4, 4, and serves as a cutting edge for the web w passed between the slide and the edge of the mouth-piece.

The operation will now be readily understood, and is substantially as follows: The attachment is first frictionally secured to the mouth-piece 2, by passing the saddle 3, 3', 3', thereover as described, after which the roll R formed by the web w is deposited in the casing 6, a sufficient section of the web being unwound to span the opening of the mouth-piece. Thereupon the slide or cover 7 is slipped into place to cover the casing and protect the web, the cover being provided with suitable openings O, O', for the exposure of the printed matter on the web, the opening O coming opposite the center of the mouth-piece, that being the point to which the conversation is directed, and toward which the eye of the speaker is most usually directed, so that the calendar is be-

fore the speaker when talking into the mouth-piece. The advertising matter A likewise comes well within the range of observation of the speaker, so that the web 5 performs the function herein ascribed to it. By impregnating the web with suitable anti-septic and germ-destroying composition, the mouth-piece is rendered absolutely sanitary. At the end of each day, the web is pulled 10 out or advanced sufficiently to expose a new calendar day through the opening O, and a fresh advertisement through the opening O', the portion of the web pulled out being severed along the cutting edge e and discarded. 15

The details of the attachment may of course be changed in many particulars without departing from the nature of the invention. It may be stated in passing that the 20 friction between the web w and the inner face of the slide 7, is sufficient to maintain the web taut at all times.

Having described my invention, what I claim is:

25 In combination with the mouth-piece of a telephone transmitter, a plate having a cut-away portion and side arms adapted to frictionally embrace the sides and the in-

termediate peripheral portion of the walls of the mouth-piece, suitable flange formations provided with marginal lips formed with the side arms aforesaid, said flanges projecting beyond the edge of the mouth-piece, a casing at one end of the plate for the housing of a tape-roll, a slide operating 30 between the flanges, and between the lips thereof and the edge of the mouth-piece, and normally extending slightly beyond the flanges and plate at the end opposite the casing whereby a cutting edge is formed, 35 the tape from the roll being adapted to be directed between the slide and the edge of the mouth-piece, and be drawn across the opening of the mouth-piece, the slide having an opening opposite the mouth-piece to 40 expose the tape to the eye, and the opening of the mouth-piece to the mouth, of the speaker, the parts operating substantially as, and for the purpose set forth.

In testimony whereof I affix my signature, 45 in presence of two witnesses.

D JACOB DANIEL.
